UNITED STATES PATENT OFFICE.

WILLIAM M. BRUCE, JR., OF SPRINGFIELD, OHIO.

TELEGRAPHY.

1,146,049.

Specification of Letters Patent.

Patented July 13, 1915.

Application filed June 15, 1914. Serial No. 845,137.

To all whom it may concern:

Be it known that I, WILLIAM M. BRUCE, Jr., a citizen of the United States, residing at Springfield, in the county of Clark and State of Ohio, have invented certain new and useful Improvements in Telegraphy, of which the following is a specification.

My invention relates to improvements in telegraphy and it particularly relates to means for insuring an even distribution of the current in cables or conductors of high capacity in sending signals so as to get a uniform marking of dots or dashes at the beginning of a series of signals when the cable is normal or where a short signal may follow a long signal during which the cable is partially discharged.

I have heretofore employed, and set forth in a pending application, a system of telegraphy in which current impulses for dots and dashes, where current reversals are employed, are automatically regulated at the sending end so that the current of different polarities is impressed upon the cable or conductor for the same length of time to insure the same rise in potential. When cables or high capacity conductors are being charged and discharged rapidly in sending a series of signals the cable does not always reach the exact normal or zero point between signals as it does after an interval of time between signals, hence the first impulse of a given polarity (with the cable normal) is apt to make a slightly longer character than the succeeding ones if they are short characters, or in the case of a long character there may be a slight space between that and the succeeding character due to the same cause, namely that the cable or conductor may reach the complete normal or zero in a long interval where it does not reach quite the normal or zero by a short interval. To this end I provide means for compensating for the residual charge in the conductor in rapid signaling and varying the amount of current impressed on the conductor at the sending end to correspond with the time intervals in the signals.

In the accompanying drawing Figures 1 and 2 are diagrams of circuits and apparatus embodying my invention. I have shown this accomplished by means of a comparatively slow or sluggish relay adapted to vary the quantity of current impressed on the conductor under different conditions of discharge said relay being adapted to be oper-

ated after the first impulses and to remain operated in the event that the impulses follow each other in normal succession, the effect being to decrease the current impressed on the conductor in starting the signals and automatically increase the current as the signaling reaches a certain predetermined speed at which the cable will not be completely discharged between impulses and affect the marking if not corrected.

In the said drawing I have shown apparatus for one end of the cable only, it being understood that this has to do only with the sending end and it is to be understood that the conductor will be properly equipped with sending apparatus at each end.

In the said drawings, *a* is an ordinary key or transmitter connected by wire 1 to a polarized relay *b*, and thence to ground at *g*. This key is normally engaged with contact *a'* which is connected by wire 2 to contact *b'* of relay *b* and by branch wire 3 to the negative side of battery *B* and by wire 4 to a contact 5 on a cut-off relay *c*. The other contact 6 of said relay being connected by wires 7 and 8 to the positive side of the battery which is also connected by wires 9 and 10 to contact *a'* of the sending key and by wire 11 to the contact *b'* of the sending relay *b*. The variable resistance relay *d* being preferably in this circuit formed by wire 11 to the contact *b'*. The armature *b'* of relay *b* is connected to the cable or conductor by wire 12 and normally includes resistance *r* and wire 13 leading from wire 12 passes to relay *c* and thence by inductive resistance *r'* to ground at *g'*. The armature *d'* of relay *d* is connected to the cable or conductor around the resistance *r* by wire 14 and wire 15 connects the opposite end of said resistance to contact *d'* of relay *d* so that when the relay *d* is energized and its armature *d'* is pulled up, the resistance *r* will be short circuited.

The operation of this system is as follows: upon pressing the key *a*, a positive impulse will be sent from battery *B* through the relay *b* from the positive pole of the battery through wires 8, 9, 10, contact *a'*, wire 1, relay *b* to ground at *g*. This will cause the polarized relay to move to contact *b'* when positive battery will be fed through wire 11 and the controlling relay *d*, contact *b'*, armature *b'*, wire 12, resistance *r* to the cable. The relay *c* will also get current through wire 13 but by reason of the inductive resistance *r'* will operate at an interval

of time later than the relay b . This will cause the armature c' of relay c to move from contact 5 to contact 6 and thus cut off the supply or positive current by grounding the positive side of the battery and will also permit the cable to discharge through wires 12, 11, 9 and 7 to ground at g^2 . The relay d being included in the circuit with wire 11 will be energized by the positive current flowing to the cable and if it remains energized the resistance r will be cut out of the main conductor circuit but if the armature c' of the cut-off c should remain for a definite period of time in position on contact 6 and the cable thereby completely discharged this relay d will be deenergized and leave the resistance r in circuit. Since the cut-off relay c works automatically this result will occur even though key a remains on contact a^2 . If the key a engages the contact a' a negative impulse is impressed on the cable by moving the armature b^3 of the sending relay b to contact b' which will also deenergize the relay d by breaking its circuit at contact b^2 thus opening the shunt around the resistance and allowing the resistance to remain in the main circuit. Now if these positive and negative impulses follow each other in rapid succession the make and break of the circuit at b^2 will, by reason of the sluggish character of this relay, cause it to remain energized and the resistance r will thus be shunted from the circuit so long as this rapid making and breaking continues. Whenever the key a remains at rest for a short period in either position this relay d will be deenergized either by the cut-off relay c changing the ground connection from the positive to the negative side of the battery or by breaking the circuit of this relay d at contact b^2 and in either case when this occurs, at a definite time interval which will permit the sluggish relay to be deenergized the resistance r will be left in the sending circuit to the cable or conductor. The result of this arrangement is that if the positive and negative impulses follow each other with sufficient rapidity to cause the cable to retain a portion of the previous charge so that it will not reach the exact normal or zero between impulses this resistance r will be cut-out while if these positive and negative impulses are separated by a time interval which will permit the cable to be completely discharged or reach the absolute zero the resistance will remain in the conductor and decrease the current impressed on the cable or conductor, the relay d being adjusted so that the time interval during which it will hold up its armature after its circuit is broken is equal to the time interval necessary for the cable to be completely discharged. The result is that any partial charge remaining in the cable due to rapid signaling will be compensated

for by said resistance to the current impulses and slightly increased current while a higher resistance and less current is provided for when the cable is at normal.

It is obvious that other methods than varying the resistance in the main conductor may be employed for varying the current to compensate for the varying cable conditions. For instance in Fig. 2 I have shown the relay d adapted to control or vary the inductive resistance r' which controls the speed of the cut-off relay c . In this case the armature d' and its back contact d^2 with wires 14 and 15 forms a shunt which normally cuts out a part of the inductive resistance r' in circuit with the cut-off relay c which causes the cut-off relay c to operate somewhat quicker when this shunt is closed than when the shunt is open. The result is that in the normal condition of the cable, the cut-off relay c will operate so as to give less current for each movement of the key than when the impulses operate each other with sufficient rapidity to cause the relay d to remain energized so as to attach its armature and open the shunt at contact d^2 thus leaving all of the inductive resistance in circuit with the cut-off relay c , causing it to operate somewhat slower and thus giving a slightly increased amount of current for each impulse to overcome the partial charge which may begin in the cable.

By the invention thus described, I am able to obtain the same amplitude on the receiving instrument at the opposite end of the cable or conductor whether the impulses be impressed on the normal or zero cable or whether impressed upon the cable before the preceding charge has been completely dissipated.

Having thus described my invention, I claim:

1. In a system of telegraphy in which current impulses of opposite polarity are impressed upon a conductor for a definite period and adapted to follow each other at different intervals, means such as described controlled by the sending impulses to vary the current impressed on the conductor as the time interval between the impulses is changed.

2. In a system of telegraphy in which current impulses of opposite polarity are impressed upon a cable for a definite period and adapted to follow each other at different intervals, means controlled by the sending impulses to vary the resistance of the conductor over which said impulses pass as the time interval between the impulses is changed.

3. In a system of telegraphy such as described, a slow or sluggish relay operated by the current impulses to vary the current fed to the conductor as the time interval between the impulses is changed.

4. In a system of telegraphy such as described means for compensating for any residual charge in a conductor whereby the rise in potential in the conductor produced by one impulse is substantially equal to that produced by succeeding impulses.

5. In a system such as described means including a sluggish relay operated by the current impulse of a series to compensate for any residual charge in the conductor whereby the rise in potential in the conductor produced by one impulse is substantially equal to that produced by succeeding impulses.

6. In a system of telegraphy, such as described, means operated by the impulses of a series to control the current fed to the conductor at the first impulse of a series to cause all of said impulses to produce in the conductor substantially the same rise in potential whether met by a residual charge or not.

In testimony whereof, I have hereunto set my hand this 5th day of June 1914.

WILLIAM M. BRUCE, JR.
